UNITED STATES PATENT OFFICE.

ELLINGWOOD H. TOWLE, OF LARCHMONT, NEW YORK.

FOLDING LANDING GEAR.

Application filed September 24, 1919. Serial No. 326,003.

To all whom it may concern:

Be it known that I, ELLINGWOOD H. TOWLE, a citizen of the United States, residing at Larchmont, in the county of Westchester and State of New York, have invented certain new and useful Improvements in Folding Landing Gears, of which the following is a specification.

This invention relates to a folding landing gear for airplanes.

The primary purpose of a folding landing gear is, of course, to decrease the head resistance of the airplane. To this end it is an object of my invention to design a landing gear which folds up along axes substantially parallel to the longitudinal axis of the fuselage, and in which the wheels, when folded, lie substantially horizontally along the bottom of the fuselage.

In landing gear folding on a transversely extending axis, the shock of landing tends to fold up the gear. In a landing gear pivoted on a longitudinally extending axis, however, the shock of landing is transmitted directly to the axis and when the wheels are unfolded has practically no tendency to fold up the landing gear.

It is a further object of my invention to design a landing gear in which the pair of arms that function to raise and lower one landing gear frame are enclosed between or straddled by the pair of arms that operate the other landing gear frame. Such a construction permits the folding of the gear. The folding, however, of the two wheels is intended to be successive rather than simultaneous.

It is a further object of my invention to provide a cover to cover up the landing gear when in its folded position so that the fuselage presents a smooth exterior to minimize air resistance.

Other objects and advantages will appear as the description proceeds.

In the drawings illustrating several embodiments of my invention,

Fig. 1 is a side view, partly in section, of an airplane fuselage showing certain parts of my landing gear.

Fig. 2 is a section on the line 2—2 of Fig. 1, looking in the direction of the arrows.

Fig. 3 is a section on the line 3—3 of Fig. 1, looking in the direction of the arrows.

Fig. 4 is a detached perspective view of the landing gear frame. 55

Fig. 5 is a view similar to Fig. 2 of a modification.

Figs. 6, 7 and 8 are a front view, side view, and sectional plan respectively of one landing wheel and associated parts, in which the landing gear is made out of piping. Fig. 8 is taken on the line 8—8 of Fig. 7.

Fig. 9 is a view similar to Fig. 2 of another modification.

Fig. 10 is an enlarged view of certain parts shown in Fig. 9. 65

Fig. 11 is a view of a joint used in the modification shown in Figs. 9 and 10.

Referring now to the drawings, the airplane fuselage, indicated at 1, carries a pair 70 of longitudinally extending beams 2 and 3, to which beams are attached the bearing plates 4. The landing gear frame comprises standards 5 connected by the horizontally extending portion 6 and braced by the diagonal braces 7. One of these frames is pivoted to each of the beams 2 and 3 on pivots 8 carried by the bearing plates 4. It will be apparent that the frame may be folded up along a longitudinal axis. The 80 bottom of the fuselage is suitably cut out, as indicated at 9, to allow the frame to fold upwardly into the same.

Each frame has mounted therein a landing wheel 10. 85

Rotatably mounted in suitable supports 11 is a threaded shaft 12 provided with a gear 13 meshing with a worm 14 carried by a shaft 15 pivoted in bearings 16, which shaft is manually rotatable by means of sprocket 90 wheels 17 and 18 and chain 19.

Two of these threaded shafts are provided for each of the landing gear frames. Engaging with each of the shafts 12 by means of a threaded collar 20 is the operating arm 21, which is pivoted to the folding frame at the point 22.

It will be apparent that rotation of the shaft 12 will lift the collars 20 and pair of arms 21 and draw up the landing gear frame. 100

The pair of arms 21', which are attached to collars 20 at their upper ends and to the other landing gear frame at their lower ends, are arranged outside of the arms 21 to straddle the same, as shown in Fig. 4. This 105 feature is important, and permits the suc-

cessive folding up of the two frames without interference. The frame operated by the arms 21 is, of course, folded up first.

The other landing gear is drawn up by means similar to the means just described, the shaft 15 and manually operating means simply being duplicated on the other side of the fuselage.

As shown in Fig. 2, the left-hand wheel and frame, which are drawn up by the arms 21 that are positioned on the inside, are drawn up first. After the wheel is in the dotted position shown in Fig. 2, then the wheel on the other side is drawn up to its position so that the two are superposed.

It should be noted that the operating arms 21 in addition to functioning as raising and lowering arms, serve to brace the wheels against the shock of landing. It should also be noted that even if the wheels are not extended to their extreme position, by virtue of the rigid connection that would be afforded by the arms 21 and threaded shafts 12, the shock of landing will be fairly well taken up in spite of this.

A door 23 sliding on guides 24 and operated by a pair of cables 25 attached at 26 and 27, slides back and forth to cover the landing gear frames when folded up, as shown in the dotted position in Fig. 2. The cables 25 may be operated by a manually operated drum 28.

Referring to Fig. 4, it will be noted that the inner pair of arms 21 are offset, as indicated at 21^a. This is to permit proper engagement of these arms with the appropriate pair of shafts 12, which must be positioned as shown to avoid interference with the left-hand frame 5 of Fig. 4.

Referring now to the modification shown in Fig. 5, the wheels 10 are carried by frames 31 and 32 pivoted at 33 and 34 on axes extending longitudinally of the fuselage, as in Fig. 1. The means for drawing up these frames, however, is somewhat different. In order to draw up the left-hand frame 31, two threaded shafts 35, only one of which is shown in Fig. 5, are provided, positioned on the same side of the fuselage as the frame 31. These threaded shafts are journaled in suitable bearings and are rotated from the handle 36 by means for the chain 37 and gears 38.

An arm 39, pivoted at 40 to the frame 31, is pivoted at 41 to another arm 42 pivoted at 43 to the bracket 44 carried by a beam 3 of the fuselage. An operating arm 45 is pivoted at the already described point 41 to arms 39 and 42. At its upper end this arm 45 is forked and engages with the threaded collar 46 that is mounted on the threaded shaft 35. It will be apparent that when the shaft 35 is rotated, the left-hand wheel 10 will be drawn up to the position shown in dotted lines.

Similar operating means are provided for the wheel on the other side; the operating arms for that wheel on the other side, corresponding to 39 and 42, are on the outside or straddle the arms 39 and 42. It should also be understood that arms 39, 42, 45, etc., are duplicated at the front and rear of the landing gear 31, and similarly the corresponding parts attached to the frame 32.

The construction shown in Figs. 6, 7 and 8 shows the modification of Fig. 5 constructed out of tubing, and corresponding reference characters indicate corresponding parts. The landing wheel 10 is supported in a fork 47.

The modification shown in Figs. 9 and 10 will now be described. In these figures the fuselage is indicated at 1. The wheel carrying frames 50 and 51 are pivoted at 52 and 53 to suitable struts 54 and 55, positioned laterally of the fuselage, so that the pivot points are farther apart than shown in the other modifications. The operating mechanism of these figures is precisely similar to that shown in Fig. 5 and need not be repeated here, the corresponding parts in the two figures being indicated by corresponding reference characters. The increased spacing between the pivot points 52 and 53 permits the wheels 10 to assume the dotted position shown in Fig. 9, where they lie against the bottom of the fuselage without overlapping.

Sliding doors similar to the door 23, shown in Fig. 1, may be used with any of the modifications shown.

In case the joint 41, Fig. 9, is made out of piping, the joint shown in Fig. 11 may be used. Arm 42 may be provided with a flattened portion 42' and arm 39 with a slot 39' to permit the arm 39 to assume the dotted position shown in Fig. 11.

While I have shown a separate manual means for drawing up each landing wheel frame, it should be understood that a single manual means could readily be provided to perform this function, it being so designed that it would draw up the two landing wheel frames successively, the frame to which is attached the inner pair of operating arms being the one to be drawn up first.

While I have illustrated certain embodiments of my invention, it should be understood that it may be carried out in other ways, and that accordingly the disclosure be considered in an illustrative sense only.

I claim as my invention:

1. In a folding landing gear, a pair of frames pivoted to the fuselage, a wheel carried by each frame, a pair of operating arms connected to each of said frames, so that one pair of said operating arms is positioned between the other pair, and means to actuate the operating arms.

2. In a folding landing gear, a pair of

frames, each pivoted on an axis extending longitudinally of the fuselage, operating arms connected to each of said frames to draw them up, threaded shafts, means operatively connecting said operating arms to said threaded shafts, and means to rotate said threaded shafts.

3. The combination as claimed in claim 1, in combination with means to cover the 10 landing gear when folded.

4. In a folding landing gear, a pair of frames, each pivoted on an axis extending longitudinally of the fuselage, operating arms connected to each of said frames to 15 draw them up, threaded shafts, means operatively connecting said operating arms to said threaded shafts, and means to rotate the said threaded shafts in combination with means to cover the landing gear when 20 folded.

5. A retractable landing gear comprising a retracting worm, a threaded sleeve upon the worm, a substantially rigid member carrying at its lower end a landing wheel, 25 connection between said member and the sleeve, and means for rotating the worm.

6. In a folding landing gear for aircraft, a pair of frames, each pivoted on an axis extending longitudinally of the fuselage of 30 said aircraft, operating arms connected to each of said frames to draw them up or to extend them, threaded shafts, means operatively connecting said operating arms to said threaded shaft, means to rotate said 35 threaded shafts, said operating arms and said frames being adapted to take all of the shock of the landing of the aircraft when the landing gear is in an extended position.

7. In a folding landing gear for aircraft, 40 a pair of frames, each pivoted on an axis extending longitudinally of the fuselage of said aircraft, operating arms connected to each of said frames to draw them up or to extend them, threaded shafts, means operatively connecting said operating arms to said threaded shaft, means to rotate said 45 threaded shafts, said landing gear being so devised that none of the shock of landing of the aircraft is transmitted to the threaded 50 shaft or to the connecting means when said landing gear is in extended position.

8. A retractable landing gear comprising a retracting worm, a threaded sleeve upon said worm, a substantially rigid member carrying at its lower end a landing wheel, an operating arm adapted to extend or retract said landing wheel, a connection between said operating arm and said sleeve, and means for rotating said worm, said operating arm and said rigid member being

adapted to receive the entire shock incident to the landing of the aircraft.

9. A retractable landing gear comprising a retracting worm, a threaded sleeve upon said worm, a substantially rigid member 65 carrying at its lower end a landing wheel, an operating arm adapted to extend or retract said landing wheel, a connection between said operating arm and said sleeve, and means for rotating said worm, said operating arm and said rigid member being so designed that none of the shock of the landing of the aircraft is transmitted to said connecting means or said retracting worm.

10. In combination, in a retractable landing gear for aircraft, a retracting worm, a threaded sleeve upon said worm, a substantially rigid member carrying at its lower end a landing wheel, operating means connected to and adapted to retract or extend said rigid carrying member, connecting means operatively connecting said threaded sleeve and said operating means for the purpose described, said rigid member and said operating means being adapted to receive all 75 of the shock incident to landing of said aircraft.

11. In combination, in a retractable landing gear for aircraft, a retracting worm, a threaded sleeve upon said worm, a substantially rigid member carrying at its lower end a landing wheel, operating means connected to and adapted to retract or extend said rigid carrying member, connecting means operatively connecting said threaded 85 sleeve and said operating means for the purpose described, said rigid member and said operating means being adapted to take all 95 of the shock incident to the landing of said aircraft, none of said shock being transmitted to the connecting means or to said sleeve.

12. In combination, in a retractable landing gear for aircraft, a retracting worm, a threaded sleeve upon said worm, a substantially rigid member carrying at its lower 105 end a landing wheel, a hinged shaft connected to and adapted to retract or extend said rigid carrying member, a connecting shaft operatively connecting said threaded sleeve and said hinged shaft at its hinged 115 portion to form a toggle joint, the two portions of said hinged shaft being adapted to form a straight line when the landing gear is in extended position, said hinged shaft and said rigid member being adapted to receive all of the shock incident to the landing of the aircraft.

In testimony whereof I affix my signature.

ELLINGWOOD H. TOWLE.
